UNITED STATES PATENT OFFICE.

MAJOR ROMEYN JEWELL, OF SENECA FALLS, NEW YORK.

DESIGN FOR A GAME-BOARD.

SPECIFICATION forming part of Design No. 29,320, dated September 6, 1898.

Application filed February 23, 1898. Serial No. 671,390. Term of patent 7 years.

To all whom it may concern:

Be it known that I, MAJOR ROMEYN JEWELL, a citizen of the United States, residing at Seneca Falls, in the county of Seneca and State of New York, have invented and produced a new and original Design for Game-Boards, of which the following is a specification, reference being had to the accompanying drawings, which form a part thereof, and in which--

Figure 1 is a top or plan view of a game-board embodying my design; and Figs. 2 and 3 are vertical sectional views taken, respectively, on the lines 2 2 and 3 3, Fig. 1.

The leading or material feature of my design consists of a rectangular board 1, having a plane or flat top surface forming a field from which projects a series of U-shaped loops 4. The U-shaped loops 4 project at right angles to the plane or flat field-surface of the board 1 and are relatively and successively arranged in a manner corresponding to the ordinary arrangement of wickets upon a croquet-field. At each end of the series of

projections 4 are arranged projecting pins or stakes 5, arising from the plane-surface field of the board 1. In the top surface of the board 1, adjacent to the edge thereof and surrounding the plane-surface field, are formed channels or depressions 2, of curved shape in cross-section, and at the intersection of the respective wings of said channels or depressions are formed circular depressions or recesses 3.

Having fully described my invention, what I claim as new, and desire to secure by Letters Patent, is—

The design for a game-board, substantially as herein shown and described.

In testimony that I claim the foregoing as my invention I have signed my name, in presence of the subscribing witnesses, this 28th day of January, 1898.

MAJOR ROMEYN JEWELL.

Witnesses:

L. M. MULLER,
M. A. KNOWLES.
